UNITED STATES PATENT OFFICE.

WALTER H. THOMAS, OF SPENCER, IOWA.

FOOT-PEDAL STRUCTURE.

Application filed May 24, 1926. Serial No. 111,237.

My invention has to do with a foot pedal structure of simple, durable and comparatively inexpensive construction intended particularly as part of a foot accelerator assembly for motor vehicles.

It is further the object of my invention to provide such a foot pedal structure so constructed and arranged that it may be assembled with as little disturbance of the parts of the car as possible.

Another object is to provide such a foot pedal having novel features of construction for making it adaptable for assembly with an accelerator operating means in such manner that the accelerator operating means such as a rod and the foot pedal need not be tied or fastened together in any way and yet may co-operate in the actuating of the accelerator.

Another object is to provide in a foot pedal of the kind mentioned, a bracket and a foot pedal proper constructed to conveniently co-operate with the bracket and to make such bracket and foot pedal by such a method of construction as to permit their ready operative connection or separation.

Still another purpose of my invention is to provide such a bracket and foot pedal and connect them with a spring in such manner as to hold them against accidental separation and also to press the foot pedal yielding against the accelerator operating member.

With these and other objects in view, my invention consists in the construction, arrangement and combination of the various parts of my foot pedal structure, whereby the objects contemplated are attained, as hereinafter more fully set forth, pointed out in my claims, and illustrated in the accompanying drawings, in which:—

Figure 1 is a perspective view of my foot pedal installed on a floor board.

Figure 2 is a longitudinal sectional view through the foot pedal and floor board showing the assembly in connection with an accelerator operating rod.

Figure 3 is a perspective view of a portion of the floor board with a carpet thereon illustrating the upwardly projecting parts of the bracket for the foot pedal; and

Figure 4 is a perspective view of the bracket. In the accompanying drawings I have

used the reference numeral 10 to indicate generally the floor board of an automobile, 55 preferably the inclined portion thereof.

On the floor board is the carpet or mat 11. It is well known that a large number of automobiles now use a foot accelerator for controlling the feed of the fuel to the 60 carburetor. Many of these accelerators have some members such as a rod 12 which projects through the floor board as for instance, through the opening 13 shown in the floor board 10. 65

I have shown the foot accelerator control rod 12 in the present instance, projecting through a hole in the mat or carpet 11. The mat 11 is provided with a mat binder or the like 14 having a central opening 70 15 to receive the rod 12.

My improved foot pedal structure includes a bracket comprising preferably a flat base member 16 having spaced opposite upwardly extending ears 17. In the forward 75 edges of the ears 17 are the bayonet slots 18, the open ends of which are their upper ends as shown.

At the center of the base 16 is an upwardly extending lug 19 provided with a 80 hole or the like 20. My improved foot pedal proper indicated generally by the reference character A, comprises a flat plate portion 21 having a peripheral downwardly extending flange 22 at the rear portion of the 85 plate 21.

The plate is provided with a raised part 23 to rest under the instep of the user. The flanges 22 at the side of the foot pedal A are formed with downward extensions or 90 ears 24 spaced forwardly from the rear end of the pedal a short distance as shown for instance in Figure 2 and connected by a cross rod or the like 25.

On the upper forward part of the foot 95 pedal is a rubber cushion or the like 26, having imbedded therein a metal member or members 27 provided with ears 28 projecting through the plate 21 and fastened thereto. 100

The under side of the plate 21 is provided with a hoop or loop or the like 29 spaced forwardly from the raised part 23 as shown in Figure 2.

One end of the coil spring 29 is fastened 105 to the loop 28 and the other end is provided

with a hook 30. I will now describe the process of installing the assembly of my improved foot pedal and the operation and some of the advantages thereof.

5 Assuming that the automobile is equipped with a foot accelerator having the foot accelerator rod 12, the mat or carpet 11 is lifted and the bracket shown in Figure 4 is fastened to the floor board 10 at the appropriate distance from the rod 12, by means of screw bolts 31 and nuts 32.

10 Slots 33 and 34 are cut in the mat 11 which is also provided with a binder ring 14. After the bracket has been installed 15 on the floor board, the carpet is dropped in place with the ears 17 and the lug 19 projecting through the slots 33 and 34.

15 The shape and arrangement of the foot 20 pedal proper A, are such that the pin or rod 25 may be slipped into the mouths 18^a of the bayonet slots 18 and then dropped downwardly to the position shown in Figure 2, whereupon the undersurface of the forward 25 end of the pedal A will rest on the upper end of the rod 12.

20 The hook 30 is inserted through the hole 20 in the lug 19. Thereupon the tension 25 of the spring 29 will tend to pull the pedal downwardly for holding the rod 25 in the bottom of the slots 18 and for pulling the forward end of the foot pedal downwardly 30 against the upper end of the rod 12. Thus provision is made against the accidental disconnection or disassembly of the foot pedal 35 A and the bracket.

35 In the actual use of my improved foot 40 pedal, it will seem that when the foot is placed upon the pedal and tilted forwardly and downwardly, the forward end of the pedal will engage the rod 12 and move it longitudinally, downwardly and forwardly 45 exerting a pushing movement thereagainst.

45 Such movement, of course, permits the upper end of the rod 12 to slide against the underside of the foot pedal which is necessary due to the pivotal mounting of the foot 50 pedal.

50 The higher the rod 12 projects through the floor board the closer its end is to the pivot of the pedal and as the rod is moved towards the support or floor board the further away its end is from such pivot.

55 The rod 12 being mounted for sliding movement, while the foot pedal is pivoted, requires a certain amount of "slippage" or free sliding movement of the end of the rod 12 relative to the foot pedal. It will be noted that my foot pedal simply rests upon the upper end of the rod 12.

60 It will, of course, be understood that the rod 12 is connected in any suitable way with the carburetor control mechanism and some means will automatically be provided whereby such rods are ordinarily held by a spring 65 at their upper rearward limits of movement.

I have not shown all of the foot accelerator structure, since the portions not shown form no part of the present invention and are well known and typical forms.

65 My foot pedal is particularly intended to be used in connection with a foot accelerator put out by the Thomas Manufacturing Company.

70 The spring actuated rod 12 will push the pedal back to normal position when pressure 75 on the pedal is released.

75 A foot pedal of this kind has a number of important advantages. There is a considerable demand for a foot accelerator of 80 the type employing a hinged pedal. The hinged pedal gives you the foot rest and facilitates more accurate and easier control of the fuel feed.

85 These pivoted foot pedals, however, give rise to a number of difficulties. It will be seen that when the foot pedal is pivoted at one end, then the other end has a pivotal connection with the rod 12.

90 The actuation of such a foot pedal will tend to cause the rod 12 to bind in the floor board because of the fact that when the foot pedal is tilted the end thereof connected with the rod 12 does not move in the line of the axis of the rod 12 but moves on the arc 95 of the circle having its center in the hinge line of the pedal.

95 It is, therefore, desirable that some mode of connection between the foot pedal and the rod 12 may be provided which will not require their being pivoted together and which 100 will permit the foot pedal to slide somewhat on the rod 12.

105 I accomplished this desirable result by pivoting my foot pedal on one end and letting it slide on the rod 12 at the other end by making the under surface of the plate 21 smooth and the foot pedal will slide free on the rod 12, resulting in a minimum tendency 110 on the part of the rod 12 to bind on the foot board.

110 At the same time the spring 29 helps to hold the forward portion of the foot pedal in contact with and in position for sliding connection on the rod 12.

115 The spring 29 also tends to hold the rear part of the foot pedal down in position where the small pin 25 will remain in the lower parts of the slots 18. However, the foot pedal proper A can be readily and quickly detached from the bracket by simply lifting up the rear end of the foot pedal 120 for moving the rod 25 out of the slots 18.

120 The hook 30 can then be quickly removed from the hole 20 whereupon the carpet may be raised and taken out if desired.

125 Another advantage in a device of this kind rises from the fact that the foot pedal and the rod 12 are not in any way fastened together and that in a structure of this kind the floor board can be readily and easily 130

lifted out without the necessity of disconnecting the foot pedal from the rod 12.

Still another advantage in the particular feature now under consideration, arises 5 from the fact that if there is a slight variation in distance between the bracket and the rod 12, no particular harm is done because the connection between the foot pedal and the rod 12 is a sliding connection only.

10 If the foot pedal and the rod 12 were pivoted together it would be of importance to always set the bracket at exactly the right distance from the rod 12, thus my device can be installed with less care, in a 15 little less time than would be possible if the foot pedal and rod 12 were actually pivoted together.

Still another advantage arises from the fact that the foot pedal and rod 12 are not 20 pivoted or otherwise connected and lies in the possibility of arranging the foot pedal at different angles, with a relation to the longitudinal axis of the car.

Thus instead of arranging the foot pedal 25 fore and aft it may be arranged at a slight angle if it is more convenient to the driver.

It is obvious that my device is very easy 30 to install and assemble or to disassemble and remove. It does not interfere at all with taking out the floor board.

The foot pedal can easily be removed from the bracket for taking out the carpet and mat. My foot pedal can be installed without cutting any large holes in the mat. 35 In fact I have shown in Figure 3 one of the devices installed where the holes in the mat can hardly be seen and the lower part of the base 16 of the bracket is covered by the mat.

It will be noted that with my foot pedal 40 the operator's foot is placed in such position thereupon that regardless of the length of driving, the foot will not become tired and this is because of the positioning of the foot pedal and the arrangement of its parts. The 45 raised part 23 projects in under the instep of the driver so that the foot or ball portion of the foot rests upon the forward part of the foot pedal with the pivot point of the foot pedal under the instep of the driver.

50 The heel of the driver rests upon the floor board and the rest of the driver's foot is supported by the foot pedal.

Attention is called to the fact that the 55 raised part 23 of the plate 21 will in actual practice rest under the instep of the driver in such a way as to afford a rest or support for the foot between the floor where the heel rests and the forward part of the foot pedal so that the foot may be rested and 60 supported if desired without imposing downward pressure on the foot or heel.

This result is accomplished by raising the part 23 far enough back from the rod 25.

65 Some changes may be made in the details of construction and arrangement of the va-

rious parts of my invention, without departing from the real spirit and purpose of my invention, and it is my intention to cover by my claims, any modified forms of structure or use of mechanical equivalents, which 70 may be reasonably included within their scope.

I claim as my invention:—

1. In a structure of the class described, the combination of a movable member such as a 75 foot accelerator rod with a bracket rigidly supported and having spaced slots therein with one of their ends open, the open ends being in a plane above the closed ends, and a foot pedal having a portion received in 80 said slots whereby said foot pedal is detachably pivoted on said bracket and having one end resting upon said member and in slid-able engagement therewith.

2. In a structure of the class described, the 85 combination of a movable member such as a foot accelerator rod with a bracket rigidly supported and having spaced slots therein with one of their ends open, the open ends being in a plane above the closed ends, and 90 a foot pedal having a portion received in said slots whereby said foot pedal is detachably pivoted on said bracket and having one end resting upon said member and in slid-able engagement therewith and means for yield-95 ingly holding the foot pedal in position as-sembled upon the bracket.

3. In a structure of the class described, the combination of a movable member such as a 100 foot accelerator rod with a bracket rigidly supported and a foot pedal detachably pivoted on said bracket and having one end resting upon said member and means for yieldingly holding said foot pedal in position 105 as-sembled upon the bracket.

4. In a structure of the class described, the combination of a movable member such as a foot accelerator rod with a bracket rigidly supported and a foot pedal detachably pivoted on said bracket and having one end 110 resting upon said member and means for yieldingly holding the foot pedal in engage-ment with said member and for yieldingly holding the foot pedal in assembled relation with the bracket.

5. In a structure of the class described in combination with a movable foot accelerator rod, a support having one portion of the rod projected therethrough, a bracket on said support spaced from the rod having a pair 115 of slots therein opening toward the rod, a foot pedal having a pivot rod secured thereto adapted to be received in said slots for detachably mounting the foot pedal upon said bracket, a spring for holding the pivot rod 120 in the closed end of said slots, the forward part of said foot pedal resting upon the end of said movable rod whereby pivotal movement of the foot pedal in one direction 125 will impart a pushing movement against 130

- the movable rod causing it to move and allowing its upper end to slide longitudinally against the underside of the foot pedal.
6. In a structure of the class described in combination with a movable foot accelerator rod, a support having one portion of the rod projected therethrough, a bracket on said support spaced from the rod having a pair of slots therein opening toward the rod, a foot pedal having a portion adapted to be received in said slots for detachably and pivotally mounting the foot pedal upon said bracket and a spring for holding said portion in the closed end of said slots.
- 15 7. In a structure of the class described in combination with a movable foot accelerator rod, a support having one portion of the rod projected therethrough, a bracket on said support spaced from the rod having a pair of slots therein opening toward the rod, a foot pedal having a pivot rod secured thereto adapted to be received in said slots for detachably mounting the foot pedal upon said bracket, a spring for holding the pivot rod in the closed end of said slots, the forward part of said foot pedal resting upon the end of said movable rod whereby pivotal movement of the foot pedal in one direction will impart a pushing movement against the movable rod causing it to move and allowing its upper end to slide longitudinally against the underside of the foot
- 20 8. In a structure of the class described, a support, a bracket mounted thereon having ears provided with bayonet slots, a foot pedal having a cross rod received in said slots and means for limiting longitudinal movement of the rod in the slots.
- 25 9. In a structure of the class described, a support, a bracket mounted thereon having ears provided with bayonet slots, a foot pedal having a cross rod received in said slots and means for limiting longitudinal movement of the rod in the slots, means for yieldingly holding the said rod in said slots.
- 30 10. In a structure of the class described, a support, a bracket mounted thereon having ears provided with bayonet slots, a foot pedal having a cross rod received in said slots and means for limiting longitudinal movement of the rod in the slots and a spring connected with said pedal and with said bracket for yieldingly holding the rod in the bottom of the slots and for yieldingly swinging the rod toward the support.
- 35 11. In a structure of the class described, a support, a bracket mounted thereon having ears provided with bayonet slots, a foot pedal having a cross rod received in said slots and means for limiting longitudinal movement of the rod in the slots, said pedal having a raised portion overhanging said brackets.
- 40 12. In a structure of the class described in combination with a movable foot accelerator rod, a support having one portion of the rod projected therethrough, a bracket on said support spaced from the rod having a pair of slots therein opening toward the rod, a foot pedal having a portion adapted to be received in said slots for detachably and pivotally mounting the foot pedal upon said bracket and a spring for holding said portion in the closed end of said slots, the forward part of said foot pedal resting upon the end of said movable rod whereby pivotal movement of the foot pedal in one direction will impart a pushing movement against the movable rod causing it to move and allowing its upper end to slide longitudinally against the underside of the foot
- 45 13. In a structure of the class described in combination with a movable foot accelerator rod, a support having one portion of the rod projected therethrough, a bracket on said support spaced from the rod having a pair of slots therein opening through one side of the bracket and having their open ends in a plane above the closed ends, a foot pedal having a portion adapted to be received in said slots for detachably and pivotally mounting the foot pedal upon said bracket and a spring for holding said portion in the closed end of said slots, the forward part of said foot pedal resting upon the end of said movable rod whereby pivotal movement of the foot pedal in one direction will impart a pushing movement against the movable rod causing it to move and allowing its upper end to slide longitudinally against the underside of the foot
- 50 14. In a structure of the class described in combination with a movable foot accelerator rod, a support having one portion of the rod projected therethrough, a bracket on said support spaced from the rod having a pair of slots therein opening through one side of the bracket and having their open ends in a plane above the closed ends, a foot pedal having a pivot rod secured thereto adapted to be received in said slots for detachably mounting the foot pedal upon said bracket, a spring for holding the pivot rod in the closed end of said slots, the forward part of said foot pedal resting upon the end of said movable rod whereby pivotal movement of the foot pedal in one direction will impart a pushing movement against the movable rod causing it to move and allowing its upper end to slide longitudinally against the underside of the foot
- 55 15. In a structure of the class described, a support, a bracket mounted thereon having ears provided with bayonet slots, a foot pedal having a cross rod received in said slots and means for limiting longitudinal movement of the rod in the slots, means for yieldingly holding the said rod in said slots.
- 60 16. In a structure of the class described, a support, a bracket mounted thereon having ears provided with bayonet slots, a foot pedal having a cross rod received in said slots and means for limiting longitudinal movement of the rod in the slots, said pedal
